UNITED STATES PATENT OFFICE.

NELSON WHITE, OF PORTLAND, OREGON, ASSIGNOR, BY MESNE ASSIGNMENTS, TO INTERNATIONAL MONEY MACHINE COMPANY, OF TERRE HAUTE, INDIANA, A CORPORATION OF INDIANA.

CHUTE-GATE FOR COIN-DELIVERY MACHINES.

1,145,727.

Specification of Letters Patent.

Patented July 6, 1915.

Application filed August 30, 1912. Serial No. 717,977.

To all whom it may concern:

Be it known that I, NELSON WHITE, a citizen of the United States, residing at Portland, in the county of Multnomah and State of Oregon, have invented certain new and useful Improvements in Chute-Gates for Coin-Delivery Machines, of which the following is a specification.

This invention has reference particularly to machines of the class designed to handle money, such as mechanical cashiers, or coin delivery or changing machines. It is quite common in this type of machines to employ a chute or chutes into which the coin or money is dropped in delivering it to the operator.

The primary object of the present invention is to provide a peculiar closure or gate for a chute of the kind referred to, though the device of the invention is susceptible of application to containers or receptacles of all classes having in view the results obtained by its use, as set forth specifically hereinafter.

The closure or gate devised by me is manually movable to open a discharge opening of the chute, and in its movement a guide co-operates therewith in an especially advantageous manner as a guide, a movement limiting means, and a latch to hold the closure in predetermined position.

A complete knowledge of the invention to enable the construction of means in accordance therewith will be obtained upon a review of the following detail description, and reference to the annexed drawings, in which:

Figure 1 is a front elevation of a chute such as used upon money handling machines of a certain type, the gate or closure means embodying the essential features of the present invention being applied to said chute to control the discharge opening of the same. Fig. 2 is a top plan view of the parts shown in Fig. 1. Fig. 3 is a rear elevation of the chute, bringing out more clearly the mounting of the guide means. Fig. 4 is a vertical transverse sectional view taken about on the line 4—4 of Fig. 1. Fig. 5 is a detail perspective view of the closure or gate alone.

In the drawings, A denotes the chute to which the closure or gate B is applied, said chute tapering downwardly toward its cen-

tral discharge opening and being of a length 55 sufficient to enable it to receive coins, or the like, from a number of different receptacles such as coin holders. In other words, the chute A illustrated is common to a plurality of receptacles the contents of which are to 60 be delivered to an operator or suitable point of deposit, through the medium of the chute. The closure B is of curved form and snugly fits against the edge portion of the chute discharge opening, as will be readily apparent upon reference to Fig. 1. A hanger 1 constitutes an integral vertical extension of the closure B, and is pivotally connected at its upper end, as shown at 2, to the chute A. Said hanger 1 is adapted to swing 70 bodily with the closure B in order to afford movement of the latter sufficient to open and close the chute discharge opening.

On the rear side of the chute A is arranged a guide 3 having offset portions 4 75 intermediate its ends to provide stops limiting the extent of swinging movement of the closure B and hanger 1 in opposite directions. The hanger 1 passes through a space between the guide 3 and the rear side of the 80 chute A. The guide 3 is peculiarly mounted, having a pivotal connection 5 with the chute A, whereby a slight rocking movement of the guide is permitted. A coiled spring 6 is connected with one end of the guide 3 85 and with the hanger 1 intermediate the ends of the latter, and performs the dual function of holding the closure B in its normal position closing the discharging opening of the chute A, and also holding the guide 3 in 90 the normal position in which it is shown in Figs. 1 and 3. The end of the guide 3 opposite that connected with the spring 6 has a pin and slot connection 7—8 with the chute A and is formed with the downwardly 95 extending finger piece 9. Between the finger piece 9 and the pivot 5 of the guide 3, the latter is formed with a catch 10. A pin 11 projects forwardly from the hanger 1 of the closure B, and is movable with said 100 hanger, the catch 10, however, being located in the path of movement of said pin, when the guide 3 is in its normal position.

The construction of the parts of the invention having been set forth, the co-action 105 of said parts will now be described. The operator by engaging his hand with the handle or finger piece 12, which projects down-

wardly from the closure B, is enabled to easily move the closure B in the direction of the catch 10, in order to open the discharge opening of the chute A and permit the contents of said chute to drop into the hand, or any other suitable point of deposit. The opening movement of the closure B is limited by the catch 10, and when the closure is released, the spring 6 will normalize the same. Obviously, under certain conditions it is desirable to maintain the closure B temporarily in open position, thus permitting coins or other articles dropped into the chute A to pass directly therefrom through its discharge opening. With this in view, the guide 3 has been mounted in the movable manner before set forth, making it only necessary for the operator to raise the end of the guide adjacent the finger piece 9, by pressure upward on said finger piece. This action elevates the catch 10 sufficiently to permit the pin 11 to pass the same, whereupon pressure on the finger piece 9 will be relieved and the catch 10 will now engage at its upper side with the pin 11 to practically lock the closure B in an open position, from which it may be released readily by again raising the guide 3 through operation of the member 9. Having in view the foregoing, it will be obvious that the guide 3 constitutes not only a guide, but a latch capable of holding the closure B in an open position. The invention comprehends that any other construction of the chute A or equivalent receptacle than that illustrated may be employed, so long as adapted to permit of the use of the closure means hereinbefore described.

Having thus described the invention, what is claimed as new is:

1. In combination, a receptacle having a discharge opening, a closure for said opening, means movably supporting the closure on the receptacle, a guide for guiding the closure in its movement, means on said guide for limiting movement of the closure, and means to move the guide into a position wherein the last mentioned means will maintain the closure in an open position.
2. In combination, a receptacle having a discharge opening, a closure for said opening, a guide member movably mounted on the receptacle in coöperation with the closure, a catch carried by said guide member for limiting the opening movement of the closure under normal conditions, and means to effect movement of the guide member to cause coöperation of said catch with the closure to hold the latter temporarily open.

3. In combination, a receptacle having an opening, a hanger mounted on the receptacle and provided with a closure for said opening, means for operating the closure to control discharge of the contents of the receptacle through the opening, a guide member pivoted at one end to the receptacle, a pin and slot connection intermediate the other end of the guide member and the receptacle, means on the hanger and the guide member for limiting the opening movement of the closure, and a finger piece projecting from the guide member for moving the same to cause the portion of the limiting means on the guide member to coact with the limiting means on the hanger whereby to maintain the closure in an open position.

4. In combination, a coin chute having a discharge opening, a movable closure for said opening, a movable latch adapted to guide the closure in its movement and to hold the closure in an open position, and a spring connected with the latch and with the closure to hold said parts in their normal positions.

5. In combination, a receptacle having an opening, a movable closure for said opening, a pivoted guide for guiding the closure in its movement, and a catch on said guide adapted to coöperate with the closure to hold it in an open position, and a spring connecting the closure and the guide for holding said parts in their normal positions, but permitting movement of the same.

6. In combination, a receptacle having a discharge opening, a movable closure for said opening, a latch having means to limit the movement of the closure and to hold said closure in open position, and a spring connecting the latch and closure to hold said parts in normal positions.

7. In combination, a receptacle having an opening, a closure for said opening and comprising a hanger pivoted to the receptacle, a guide member pivoted to the receptacle and having a catch, a pin on the hanger adapted to engage said catch to limit the opening movement of the closure, and adapted for a different engagement with the catch to maintain the closure in an open position, means for manipulating the guide, and means for holding the parts in their normal positions.

In testimony whereof I affix my signature in presence of two witnesses.

NELSON WHITE.
